JAMES STANMORE AND DAVID KENNEDY, OF SEATTLE, WASHINGTON.

BOLTING-UP DEVICE.

1,415,726.

Specification of Letters Patent. Patented May 9, 1922.

Application filed July 30, 1919. Serial No. 314,217.

To all whom it may concern:

Be it known that we, JAMES STANMORE and DAVID KENNEDY, citizens of the United States, residing at Seattle, in the county of King and State of Washington, have invented certain new and useful Improvements in Bolting-Up Devices, of which the following is a specification.

This invention relates to improvement in clamps, and particularly to that class known as "bolter-ups."

In devices hitherto employed for drawing metal plates of structural work together preparatory to uniting the same by rivets, a number of defects exist which it is the object of this invention to obviate.

Some of the devices are of relatively large size and heavy, while others are in the nature of machines which require much attention and frequent adjustments to keep in order.

All of them, as far as we know, however, are more or less imperfect, laborious to use, slow in action and require so much space in which to operate that they are unsuited for work in many places, as in the tanks of ships.

The object of our invention is to overcome the above mentioned and other difficulties by the provision of an inexpensive, strong and durable bolting-up device which is constructed of a minimum number of parts.

Another object is to provide a device of this character which may be quickly applied and conveniently operated.

With these and other ends in view, the invention consists in the novel construction, adaptation and combination of parts as will be hereinafter described and claimed.

In the accompanying drawings, Figure 1 is a view partly in elevation and partly in longitudinal section of our improved bolting-up device shown applied. Fig. 2 is a similar view taken at right angles to the plane of Fig. 1 and showing the work parts in different relative position.

Fig. 3 is a perspective view of the post member of the device; and Fig. 4 is a perspective view of the sleeve member thereof. Fig. 5 is a side elevational view of a wedge which may be substituted for the wedge shown in Fig. 2.

Referring to the drawings, the numerals 5 and 6 designate plates to illustrate the application of the present invention. The plates being shown in Fig. 1 in spaced relations and in Fig. 2 they are shown as drawn

together through the instrumentality of our device for the purpose of securing them by means of suitable fasteners, such as rivets.

In carrying out our invention there is provided a post member comprising a cylindrical body portion 7 having a relatively large head 8 at one end and a screw threaded stud 9 extending axially from its other end.

Extending diametrically through said body element 7 is a slot 10 which is coextensive with a seat 10¹ of semicircular form, preferably, provided in the head element 8.

Fitted to the body element 7 of the post member is an annulus or sleeve 11 having an external diameter of the same diameter, desirably, as the head 8.

In the end of the sleeve adjacent to said head are provided two pairs of notches which are respectively indicated by 12, 12¹ and 13, 13¹. The complementary notches of each pair being disposed at diametrically opposite sides of the sleeve and, as shown in Fig. 4, one pair of notches is, by preference, arranged in right angular relation with respect to the other pair.

The inner ends as 12² and 13² of the respective notches are arranged in planes inclined from the axis of the sleeve. 14 and 15 represent tapering pins adapted to be driven through the slot and notches of the post and sleeve members.

Said pins are of slightly less thickness than the width of said slot, with parallel side faces 16, a plane edge face 17 and a curved edge face 18. The angular relation between the edges 17 and 18 of a pin corresponds with the inclination of the plane of the notch faces 12² or 13² of the sleeve with respect to a plane extending at right angles through the sleeve axis so that the sleeve will have bearings at diametrically opposite sides against the pin. The device is further provided with a nut 19 engageable on the screw threads of the post stud 9.

With the sleeve 11 on the body 7 of the post member, the stud of the latter is inserted through holes 5¹ and 6¹ of the plates 5 and 6, the nut 19 is engaged with the stud threads and screwed down on the stud into contact with the outer plate face 6².

The smaller pin is then introduced through a pair of the sleeve notches, as 12, 12¹ for example, and also through the post slot 10 with the rounded edge of the pin bearing against the seat 10¹ in the head.

The operator then drives with a hammer

against the larger end of the pin to force the latter further through the device, resulting in the pin acting as a wedge between the seat 10¹ and the inner ends, as 5 12², of the slots causing the sleeve to be forced against the plate 5 to draw the same against the other plate 6 which is held by the nut 19. Where there is considerable 10 space between the plates the smaller and larger wedge pins may be used successively, the distance taken up by the smaller pin being retained while substituting pins by means, for instance, of a bolt passing 15 through a pair of registering plate holes adjacent to the holes which are utilized with our device.

The referred to bolt and the holes therefor are not shown in the drawings.

The use of a device employing driving 20 wedge affords a most powerful, convenient and rapid manner for drawing plates together.

What we claim, is—

1. A bolting-up device comprising a post 25 member having a body element with a slot extending diametrically therethrough, a screw threaded stud extending axially from said body element, a nut engaging the screw thread of said stud, a sleeve provided at 30 one end with notches having inclined inner faces, and a wedge adapted to be driven through the body slot and the notches of said sleeve to force the latter toward said nut.
- 35 2. A bolting-up device comprising a post member having a body element, a head element at one end of the body element and a stud element at the other end, a slot extending diametrically through the body and

head elements, plate-engageable means 40 mounted on said body element and provided at one end with notches at diametrically opposite sides, and a driving wedge adapted to be inserted through said slot and notches.

3. A bolting-up device comprising a post 45 member provided with a body element having a slot extending diametrically therethrough, and a screw threaded stud element extending axially from said body element, a nut engageable on said stud element, a driving wedge inserted in the post slot, and a sleeve slidably mounted on said body element between said driving wedge and said nut, said sleeve being provided at one end with wedge bearing surfaces disposed in inclined relations to the axis of the sleeve.

4. A device for drawing together two plates, said device comprising a post member having one of its ends adapted to be 60 passed through both of the plates, said post being provided with a diametrically disposed slot, plate engaging means provided on said post in spaced relation from said slot, a sleeve slidably mounted on said post, 65 and a wedge-shaped pin adapted to be driven through the post slot between one end of the latter and said sleeve whereby the sleeve and said means are actuated to draw the interposed plates together.

Signed at Seattle, Washington, this 17th day of July, 1919.

JAMES STANMORE.
DAVID KENNEDY.
